UNITED STATES PATENT OFFICE.

GEORGE S. OTEY, OF DALLAS, TEXAS, ASSIGNOR TO THE HESSE ENVELOPE COMPANY,
OF DALLAS, TEXAS, A CORPORATION OF TEXAS.

ENVELOP-MACHINE.

1,203,904.

Specification of Letters Patent.

Patented Nov. 7, 1916.

Application filed February 20, 1915. Serial No. 9,484.

To all whom it may concern:

Be it known that I, GEORGE S. OTEY, citizen of the United States of America, residing at Dallas, Dallas county, Texas, have invented certain new and useful Improvements in Envelop-Machines, of which the following is a specification.

This invention relates to envelop manufacturing machines and more particularly 10 is this invention an attachment for envelop machines, adaptable either as an attachment applicable to any standard type machine of present day manufacture or capable in itself of becoming a new and original machine.

15 Primarily the purpose of the invention is to produce an attachment, adapted to correlate with standard type envelop manufacturing machines in applying transparent patches to the aperture which is cut or died out in 20 the envelop blank; the perfected envelop being of the class known as the outlook or time-saver envelop. Further, the purpose is to produce such an attachment or mechanism whose function shall be to speedily and 25 accurately deliver, from a magazine of transparent patches, a single patch to a plunger where it will be instantly released by the delivering agent and simultaneously grasped and retained by the plunger, which plunger 30 in its downward stroke carries the patch to the envelop blank where it is applied over the aperture or window of the envelop blank.

The invention is designed to use air suction as its primary transmitting agent in 35 handling the patch and blank, the plunger making delivery of same to the folding box where the blank is folded and transformed into a perfect envelop; means for admitting an air pressure, or the normal atmosphere, 40 being provided, the purpose of which is to instantly destroy the vacuum set up in one of the elements by the suction means.

A primarily broad feature of the invention is the provision of an air or suction 45 timing mechanism which will positively and accurately handle the very light weight and thin transparent patch, speedily delivering it, on each cycle of operation, to the desired place.

50 Further, the invention embodies a pivoted patch carrier which is formed hollow, pressure below normal atmospheric pressure being maintained in it and released at proper times, for the purpose of picking up and let-

ting go the patch at the proper point in the 55 cycle of operation.

Still further features of the invention reside in the various controlling and timing means which are used for properly setting up and timing the exhaust and pressure 60 through the various operative elements.

With these and other objects in view the invention has relation to certain arrangements and combinations of parts, an example of which is described in the following specification, set out in the appended claims and illustrated in the accompanying drawings wherein:

Figure 1 is a rear elevation of certain parts of an envelop machine having embodied thereon the attachment which is the subject of this invention. Only enough of the machine is illustrated to properly describe the invention, those parts of the machine which are not directly related to the 70 invention being omitted. Fig. 2 is a side elevation of Fig. 1, some parts being illustrated in section. Fig. 3 is a detailed view of the attachment detached from the machine proper. Fig. 4 is a side view of parts of the 75 attachment. Fig. 5 is a sectional side elevation of parts of the attachment, showing different operative positions of the parts. Fig. 6 is a view of the bottom of the particular form of plunger used. Fig. 7 is a top 80 view of the particular form of envelop trap embodied in the folding box. Fig. 8 is a view of an outspread envelop blank with a transparent patch applied thereto. Fig. 9 is a view of an envelop showing the window 85 cut therein and the gum applied to the flaps and around the window. Fig. 10 is a detailed view of a slotted actuating rod embodied in the invention.

Referring now more in particular to the 90 drawings wherein the same reference characters designate identical parts, the numeral 1 designates the main drive shaft of any well known type of envelop machine, the same being journaled in the frame 2. Portions of the upper frame have been broken away, eliminating many of the operating elements and illustrating in connection with the invention only those elements of the standard type envelop machine which are 95 absolutely necessary to properly describe and illustrate the invention.

The cross bar 3 of the frame carries and

supports a substantially large yoke 4. An envelop plunger 5, of a particular construction hereinafter more fully described, is carried on the lower extremity of a vertical hollow plunger shaft 6. Said hollow shaft is adapted to undergo a vertical reciprocation and is confined in the bearings 7 of the frame and yoke. A cross arm 8 is fixed to the plunger shaft. Said cross arm is provided with guides 9 adapted to reciprocate in contact upon tracks 10 formed on the member 4. A pair of links 8^a are pivotally correlated with the cross arm serving to reciprocate, from a driving mechanism not shown, the plunger.

A table 11 is embodied within the frame and adapted to support various operating elements which are in no way correlated with this invention, hence they are omitted from this description and illustration. However, the folding box, that combination of elements which creases and folds the envelop, is here partially illustrated; and consists of the folding members 12 and 13 which are pivoted to the table and adapted to undergo a certain movement about their pivotal point, said movement being controlled through members which are not associated with the invention and are therefore omitted. Also the trap 12^a forms a part of the folding box and is pivoted to the under surface of the table. Said trap is of a particular construction as will herein-after appear in detail. As each envelop is folded in the folding box the trap will drop or pivot down causing the completed envelop to be dropped in the drying rack, not shown.

The elevator 14 which generally carries the stack of envelop blanks is mounted in a usual form of track support which depends from the table 11. This elevator consists of the member 14 having integrally formed therewith vertical guides 16 which are confined in the track 15. This elevator, as understood by those conversant with the art, is provided with means for raising and lowering it in the track. In this instance a hand wheel 17 is fixed to a shaft 18 which carries pinion 19 adapted to engage a rack 20, which is confined in the track 15. A ratchet wheel 21 and pawl 22 are provided to hold the elevator in its upper positions against the force of the weight of its supply of envelops. In Fig. 2 the elevator is in its lower position and carries a supply of envelop blanks.

A picker plate 23, also known in the art as a stripper plate, is here illustrated. In Fig. 2 said member is shown in section, illustrating the several apertures through which the picker plunger or gummer descends until it is in contact with the top envelop blank, carrying same up to a conveyer mechanism 24, whereby the blank is delivered to the

descending plunger 5 which carries it to the folding box where it is immediately transformed into an envelop, either of the ordinary type or of the outlook or time-saver type, that being dependent upon whether or not the machine is equipped with this attachment comprising the invention.

During the operation of the machine the elevator is adjusted high enough for the top of the stack of blanks to be adjacent to the under surface of the stripper plate. As the pickers descend through the apertures of the stripper plate and gum the top blank, said blank will adhere or stick to the gummed picker which will immediately start on its return trip when the top blank will be picked from the picker by the plate, which operation merely allows the blank-conveyer to pass under the blank adhering to the gummer and carry it to the plunger.

The mechanism just described and which relates to the various movements of those elements which control the envelop blank in its passage through the machine is in no way, with one exception which will herein-after appear in detail, correlated with the invention, hence the description and illustration of those few parts.

Generally speaking, the foregoing description may be taken to apply to a machine to which the attachment can be quickly and conveniently attached, the following being a more specific description of the invention and attachment.

A three-way valve 25 is mounted upon the side of the yoke and is provided with a control arm 26. A vertical actuating rod 27 is slidably carried in bearings 28 integral with and projecting from the member 4. The control arm is passed through a slot in and correlated with the actuating rod as shown in Fig. 10 which gives a free movement between the two members. Trip members 29 are fixed to the extremities of the actuating rod. Contact lugs 30 are carried by each extremity of the cross arm 8 and projected beyond the tracks 10 and lie within the vertical path of the trip members. The valve 25 is provided with an inlet port 31, for air of atmospheric pressure and a suction port 32. A substantially large pipe line 33, which for convenience, lies on the floor and extends to the machine, is connected to some suction device (not shown) such as a tank which is being subjected to a continuous exhaustion of the air contained in it. A slightly smaller pipe 34 has connection with the main line and extends upward through the machine. A flexible tubing 35 connects the suction means with the valve 25; which valve will be later seen to accurately time, through its associated control devices, the suction through the several elements, whose function it is to handle the envelop blanks and the transparent patches.

A flexible tube 36 connects the valve 25 and the hollow plunger shaft; said valve serving to time the suction through the tube 36 into the hollow shaft at the proper time.

3 An inlet valve 37 of similar construction to the valve 25 is fixed to the frame or member 4 and has associated with it similar elements to those correlated with the valve 25 and previously described. Said valve 37 is provided with the inlet port 38. A flexible tube 39 connects the valve 37 to the hollow plunger shaft 6, and as later seen is adapted to open and allow a flow of normal pressure into the member 6.

35 A valve 40 similar to the valve 25 is mounted upon the table 11 and provided with a control arm 41. A pipe or tube 42 connects the valve with the main exhaust line.

40 A pivoted patch carrier, comprising a number of hollow suction nozzles 43 carried by and opening into a tubular shaft 44 which is journaled in a pair of journal brackets 45 fixed to the frame, is provided. Collars 46 fixed to the tubular shaft serve to prevent longitudinal movement of the shaft, limiting it to an oscillatory movement, as later described. The suction nozzles are provided on their extremities with the apertures 47 which are formed in a contact face 48 bevelled on the free extremity of the members. Said nozzles are accurately alined upon the tubular shaft and adapted to speedily and accurately perform the function of delivering the delicate patches from a magazine to the plunger, a further description of which appears hereinafter. A tube or other flexible connection 49 connects the valve 25 with the patch carrier. An actuating arm 50 is fixed to the tubular member 44 and as later seen is instrumental in subjecting the pivoted patch carrier to a partial rotation about its axis. A cam 51 is fixed to the main driving shaft of the machine. It will be understood that the driving shaft is the agent for driving the many and various elements of an envelop machine, and is usually crowded with cams and various devices; but to those experienced in the art it will be clear that room on the shaft can be had for the single cam which is used to control the attachment. Connecting links 52 and 53 respectively have pivotal connection with the actuating arm 50 and the control arm of the valve 40. The lower extremities of the two links carry a cam roller 54 which rolls in contact with the cam. Links 55 have a pivotal connection with the frame and with the pin carrying the roller, and serve to take the thrust and strain of the turning cam from the links 52 and 53. A spring or other means may be correlated with the links to keep the cam roller in positive contact with the cam.

45 The trap 12 is formed hollow and has a

flexible tube connection 56 with the valve 40. Said trap has its upper surface finished on a horizontal plane and adapted to receive the envelop blank and retain same till the folding is completed. A plurality of apertures 70 57 is provided, opening from the hollow trap to the atmosphere.

5 A description will now be given of the plunger 5 which is instrumental in folding the blank as said plunger descends into the 75 folding box. The plunger is of hollow construction, having its lower face finished on a plane horizontal which adapts the adjacent faces of the plunger and trap to properly contact. A number of transverse slots 58 80 are formed in the plunger and are equal in number to the suction nozzles 43; and are alined with and lie within the path of revolution of the oscillating nozzles 43. The hollow shaft 6 opens directly into the hollow 85 plunger, the working surface of the plunger being provided with a plurality of apertures 59.

8 A description will now be given of the magazine which carries a quantity of transparent patches, holding the patches accessible to the patch carrier, exposing an individual patch to said carrier upon each cycle of operation. It should be further understood that this particular type of magazine 90 is not essential to the proper operation of the machine but is concisely described as an example of a magazine which will properly perform the purpose of retaining a quantity of patches and delivering a single one to the 95 patch carrier.

9 A pair of vertical members 59 have their lower extremities slotted, as indicated by numeral 60; a substantially large screw 61 is passed through the slot and screw threaded 100 into the table. A reach bar 62 is carried by the upper extremities of the members 59 and is provided with adjusting means which allows said reach bar to be subjected to a 105 rotative adjustment. Support members 63 are 110 fixed to the reach bar in a substantial and rigid manner. The reach bar is so adjusted as to allow the free extremities of the members 63 to be tilted slightly downward from the horizontal. Members 64 are adjustably 115 retained, through the agency of a screw 65 threaded into a support 66 similarly held by the reach bar. A quantity of transparent patches are placed upon and within the magazine as illustrated and with the tips of the 120 members 64, which are reduced in size, inwardly bent to barely catch and retain the blanks upon the supports 63. The points of the members 64 are delicately adjusted just in front of the quantity of patches sufficient 125 to hold same but readily release the first patch at the proper time of delivery. A weight 69, preferably of the same shape and size of a patch, is laid behind the quantity 130 of patches and adapted to keep the patches

pressed forward in engagement with the points of members 64.

It should be understood that this machine is adapted to handle any size and shape patch, the one here illustrated merely being an example of one shape of patch which can be easily handled by the machine.

The position of the elevator 14 in Fig. 1 is shown in its lowermost position to which it had been lowered to be refilled with envelop blanks. When the supply of blanks becomes low or runs out the ratchet mechanism was released by the operator which allowed the elevator to descend to the position shown. Associated with the invention is means for cutting off the suction from the system and particularly from the patch carrier.

A cut-off valve 70 is provided in the suction line. A substantially long depending control rod 71 is correlated with the valve and lies along and adjacent to the path of travel of the elevator 14. Trip members 72 are fixed to the member 71 and project over and within the vertical path of travel of the elevator 14. The lower extremity of the control rod 71 is slidably retained by a bracket 73 which is in fact rigidly mounted on portions of the frame not shown.

In its lowermost position as illustrated in Fig. 1 the elevator has engaged the lower trip finger causing the member 71 to undergo a downward displacement thereby closing the valve 70 and shutting off the suction from the valve 25 which cuts off the suction from all elements which are controlled by the said valve. This is seen to be an automatic means for stopping the suction flow through the pivoted carrier; which is necessary to prevent the picking off of the patches while the machine is running and while the operator is placing on the elevator a new supply of blanks. Also this described element of the invention contributes to economical use of the air exhausting device as it allows the suction to pass through the pivoted carrier and plunger only when said elements are in the actual operation of carrying the blanks and patches. When the elevator is given its upward movement and the blanks are brought adjacent to the stripper plate, as shown in Fig. 5, ready for delivery, the upper trip finger 72 is contacted which causes the valve 70 to be opened.

Figs. 8 and 9 are views of envelop blanks showing the slotted opening or window 6 formed in the blank and covered by a transparent patch *c*. The numeral *d* designates the gum around the window which is placed on the blank before said blank reaches the plunger. When the patch is applied over the window it adheres to the gum under the pressure of the folding devices of the folding box.

A description will now be given of the

operation of the machine with a view of further explaining the principles and functions of the invention. Particular attention to Figs. 4 and 5 in connection with all the views will give the location and disposition of parts during the periods of each cycle of operation.

The machine will be assumed in operation, which sets the various elements of the invention in motion. The position of the various moving parts in Fig. 1 is taken as the plunger is going up, at which time the said plunger is relieved from the patch and blank which it previously carried down. The patch carrier, through the agency of the link 52, has just picked off, by suction, a patch from the magazine and is carrying it about its arc of revolution, toward the plunger which by this time has reached its uppermost position as shown in Fig. 5, at 75 which time the patch carrier suction nozzles have passed up into the slots 58 of the plunger. At this point the contact points 30 have impinged the upper trip members 29 causing the valve 25 to stop the suction 80 through the tube 49 and patch carrier which releases the blank *c* from the patch carrier; and the valve 37 so set as to stop the admission of air, through the port 38, to the plunger. Simultaneously with this release 85 (or to be more accurate, slightly before), the suction is opened through the tube 36 and hollow plunger. The suction immediately grasps and holds the patch. This position of plunger and suction nozzles is 90 shown in Fig. 5. The contact lug or point 30, which is correlated with the reciprocating plunger shaft, impinged the upper trip member 29 which controls the valve 37 just before the valve 25 was actuated. This action took place just before the suction was diverted into the hollow plunger and closed the valve 37, thereby stopping the admission of air to the plunger, which was admitted to destroy the partial vacuum while 95 the plunger was down, and making it possible for a partial vacuum to be created within the plunger at the instant said plunger was at the top. It will be understood that the plunger is now retaining a patch. Said 100 plunger immediately starts downward carrying the patch. This position is illustrated by reference character A in Fig. 5. At this stage of the operation the conveyer mechanism 24, through its associated control, has brought into position directly in the path of the moving plunger, an envelop blank which is taken down by the hollow plunger, position B, Fig. 5, (which is all the time having a high suction) and carried into 105 the folding box and against the hollow trap. Simultaneously with reaching the trap the contact point on the end of the cross arm changes the setting of the valve 25 so as 110 to divert the suction from the plunger back 115 into the plunger. The plunger continues 120 downward until it reaches the bottom of the plunger tube, at which time the contact point 30 125 impinges the lower trip member 29, which actuates the valve 37 so as to open the suction 130 tube 36 and close the valve 25.

to the patch carrier. Prior to this last action on the part of the valve 25, the patch carrier was traveling back toward the magazine; it reached the magazine just at the time the suction was diverted from the plunger to the nozzles of the carrier. This suction through the ports 47 causes the carrier nozzles to pick off a single patch from the magazine at which time the carrier starts toward the plunger as previously described. During the descent of the plunger the inlet valve 37 was closed; when the contact point 30 which controls the valve 37 impinged, in its lowermost position, the lower trip members 29 the inlet valve was opened which allowed air, at normal pressure, to flow into the port 38, destroying the partial vacuum which was previously in the plunger. This action immediately releases the suction hold on the envelop blank and patch. Simultaneously with the flow of air into the plunger from the valve 37 (or to be more accurate, slightly before), the link 53 changes the setting of the valve 40 which sets up a suction throughout the hollow trap which was heretofore at normal air pressure. This suction in the trap, which was set up just as the plunger descended onto the trap, picks off the envelop-blank and patch from the plunger and holds same as the plunger ascends for the next cycle. At this stage of the operation the several folding devices 12 and 13 are closed, by means not shown, in upon the blank and patch, carrying down the tabs and edges of the envelop and sticking same against the gummed portions completing the envelop. By the time the folding has been completed the valve 40 has again assumed its normal position, as illustrated, which allows the air to pass into the ports of the trap, destroying the partial vacuum previously set up therein, thereby causing said trap to release its hold on the finished envelop. At this time the trap is acted upon by its well known control devices, not shown, which swing the front edge downward allowing the envelop to fall from the machine bearing a perfectly applied transparent patch. The finished envelop is precipitated from the trap into the drying rack not shown. As the trap is delivering its finished envelop all parts are traveling to their original position prior to the next cycle of operation or delivery of another blank and patch to the plunger and folding box.

The several primary elements of the invention which are provided with perforations or apertures in their working faces, preferably have said perforations formed of very small diameter and of a great number and close together; this will cause the blank and patch to closely adhere, under the suction to which they are subjected, to each successive element, which carries the patch and blank.

Envelop machines in present use are not provided with air suction means for pulling the blank from the plunger, but depend upon various means, as gum for instance, all of which necessitate running the machine at a moderately low speed. The present invention is devoid of all such means or appliances for performing said function, air suction alone being used to pull the blank from the plunger, which allows a very high rate of speed of production of envelops per hour.

Broadly stated the invention embodies a multiplicity of air suction means and admission elements all properly timed and adapted to properly handle the blank envelopes and patches.

This invention is presented as including all such modifications and changes which may properly come within the scope of the following claims.

Claims:

1. In an envelop machine the combination with a frame, of a trap having suction openings pivoted on the frame, a plunger provided with slots adapted to deliver a patch to the trap and also provided with suction openings, a tubular shaft journaled on the frame, patch carriers provided with suction passages carried by said tubular shaft and adapted to convey a patch to the plunger, the slots of said plunger adapted to receive said patch carriers, and a suction means connected with said trap, plunger and carrier.

2. In an attachment for envelop machines, the combination of a hollow creaser plunger, a tubular rock shaft horizontally journaled adjacent to the path of travel of said creaser plunger, a plurality of suction nozzles carried by said tubular rock shaft and adapted to deliver a patch to said plunger, the free extremities of said suction nozzles formed on an angle, an actuating arm fixed to said rock shaft, a link pivoted to said actuating arm, and a cam adapted to reciprocate the link.

3. In an envelop machine, the combination of a hollow plunger shaft, a hollow plunger provided with apertures carried by said shaft, a trap provided with apertures positioned beneath the plunger and adapted to receive a patch from the plunger, a hollow pivoted patch carrier disposed in operative relation with the plunger and adapted to convey a patch thereto, suction means connected with the apertures of the trap, with said patch carrier, and with the hollow plunger, and means for controlling the suction therein.

4. In an envelop machine, the combination of a hollow plunger shaft, a hollow plunger provided with apertures carried by said shaft, a trap provided with apertures adapted to receive the patch from the plunger, a patch carrier having suction apertures

adapted to convey a patch to the plunger, and suction means communicating with the apertures in the trap, patch carrier and hollow plunger, and means for controlling the 5 suction therein.

5. In an envelop machine, the combination of a hollow plunger shaft, a hollow plunger provided with apertures carried by said shaft, a suction control valve communicating 10 with the plunger, an air admission valve communicating with the apertures of the plunger, a rotatable tubular shaft journaled on the frame, suction nozzles provided with apertures formed in their extremities carried 15 by the tubular shaft, and a suction means connected with the tubular shaft and with said control valve.

6. In an envelop machine, the combination of a hollow plunger shaft, a plunger 20 provided with apertures carried by said shaft, a suction control valve communicating with the apertures of the plunger, an inlet valve communicating with the apertures of the plunger, a rotatable tubular 25 shaft journaled on the frame, suction nozzles provided with apertures carried by the tubular shaft, suction means connected with the tubular shaft and suction control valve, and a cam adapted to control the operation 30 of the associated tubular shaft and suction nozzles.

7. In an envelop machine, the combination of a hollow plunger shaft, a plunger carried by said shaft, a cross arm carried 35 by the said plunger shaft, lugs formed on the cross arm, a suction control valve connected with the hollow plunger, a pivoted patch carrier in operative relation with said plunger and adapted to deliver a patch to 40 the plunger, and an actuating rod adapted to control said valve and operated by one of said lugs.

8. In an envelop machine, the combination of a hollow plunger shaft, a plunger 45 provided with apertures carried by said shaft, a suction control valve having communication with the plunger, a hollow pivoted patch carrier having communication with the suction control valve and adapted 50 to deliver a patch to the plunger, a trap disposed beneath the plunger and adapted to receive a patch from said plunger, a valve having communication with said trap, a cam adapted to actuate said valve, a link 55 connected with the suction control valve, a link connected with the second valve recited, and a cam roller journaled in the extremities of the links and in operative contact with the said cam.

60 9. In an envelop machine, the combination of a hollow plunger shaft, a plunger provided with apertures carried by said shaft, a suction control valve communicat-

ing with the plunger, a hollow pivoted 65 patch carrier adapted to convey a patch to said plunger, a hollow trap adapted to receive the patch from the plunger, a valve connected with said trap, means provided for controlling the valves, and suction means 70 connected with the patch carrier, plunger and trap.

10. In an envelop machine, the combination of a hollow plunger shaft, a hollow plunger carried by said shaft, a hollow trap 75 disposed beneath the plunger and adapted to receive a patch therefrom, a tubular rock shaft journaled on the frame, arms provided with suction passages carried by said rock shaft and adapted to swing up in 80 proximity to the plunger and deliver a patch directly to said plunger, suction means connected with the elements recited and means for controlling the suction therein.

11. In an envelop machine, the combination of a creaser plunger provided with slots, a patch carrier provided with suction passengers adapted to deliver a patch to the creaser plunger, suction means connected 90 with the patch carrier and said plunger, and said patch carrier adapted to pass into the slots of the plunger and deliver a patch directly from the patch carrier to the plunger and means to control the suction therein.

12. In an attachment for envelop machines, the combination with a frame, of a hollow creaser plunger journaled in said frame and adapted to reciprocate, a hollow rock shaft journaled upon the frame, a plurality of hollow patch carriers carried by said rock shaft and adapted to convey a patch to the plunger, means provided for oscillating said patch carriers in synchrony with the reciprocating creaser plunger and 105 means for controlling the suction in the plunger and patch carrier.

13. In an attachment for envelop machines, the combination with a hollow plunger with slots provided therein, of a 110 tubular shaft, suction nozzles carried by said tubular shaft, means provided to subject the tubular shaft and suction nozzles to a regularly timed oscillatory movement to cause said nozzles to enter said slots, said suction nozzles having a beveled construction on the ends thereof adapting said oscillating nozzles to pass into the slots of the plunger with the working faces of the plunger and suction nozzles in a flush and 115 even relation one to the other.

In testimony whereof, I affix my signature in the presence of two witnesses.

GEORGE S. OTEY.
